UNITED STATES PATENT OFFICE.

FRITZ LOWENSTEIN, OF BROOKLYN, NEW YORK.

SPARK-GAP APPARATUS.

1,388,834.

Specification of Letters Patent. Patented Aug. 23, 1921.

Application filed January 19, 1918. Serial No. 212,616.

To all whom it may concern:

Be it known that I, FRITZ LOWENSTEIN, a citizen of the United States, residing at Brooklyn, county of Kings, and State of New York, have invented certain new and useful Improvements in Spark-Gap Apparatus; and I do hereby declare the following to be a full, clear, and exact description of the invention, such as will enable others skilled in the art to which it appertains to make and use the same.

This invention relates to radio signaling apparatus. In particular, it has to do with a novel type of quenched spark gap apparatus for use in radio transmitter systems.

In what is generally known in the radio art as the quenched gap, the total operating gap length or distance is split up into a plurality of relatively minute gap distances which are in series electrically and whose sum gives the necessary length and power of disruptive spark discharge necessary for operation under given conditions. The advantages of a quenched gap, as against the older type of single full length gap, are well known in the art and require no recital here. The use of the quenched gap has been attended, however, with certain difficulties and drawbacks in practical radio work which it is the main object of this invention to overcome, while also attaining better operation and greatly increased convenience and general efficiency. In this connection reference is here made to my prior application, copending herewith, Ser. No. 858,499, filed August 25, 1914, which has matured into Patent No. 1,305,816, of June 3, 1919, in which certain broad features characterizing the invention hereinafter set forth and claimed, are disclosed. Said prior application relates particularly to quenched tubular gaps. The present disclosure has to do more especially with quenched gaps of the plate or disk type, though in its broader aspects the invention is not limited thereto.

Among the disadvantages inherent in quenched spark gap apparatus proposed prior to my invention was the difficulty of removing and replacing individual gap units from the assembled series when necessary. The entire gap had to be taken apart and reassembled, an operation which required considerable technical skill and which involved serious delay and inconvenience. One of the objects of my invention is to provide a quenched spark gap of such improved con-

struction that any one of the component gap units, which may comprise a single elemental gap or several elemental gaps, can be readily removed and replaced independently of the rest and without in any way disturbing their relation to one another. In particular, the object of the invention in this respect is to provide a plate gap construction of the aforesaid desirable characteristics, that is, a quenched gap in which the component gap units consist of pairs of spaced plates or disks, constituting electrodes between which the elemental spark discharges occur serially.

The problem of properly cooling quenched gaps, especially gaps of any considerable power, has also been a serious one. Cooling by means of a fan has been commonly resorted to, but this requires auxiliary apparatus and introduces attendant complications which it is often desirable or essential to avoid. Self-cooled gaps have been known heretofore, but they have been characterized by massive heat-radiating surfaces of large size and weight, rendering the gap very bulky, heavy, and unsuited for use except where economy of space and ready portability of apparatus are of no particular consequence. An important object of the present invention is to provide a self-cooled gap whose size and weight for a given power rating are very much less than has been possible heretofore.

Another object of the invention is to enable the effective number of gap units or elements in circuit to be varied easily and rapidly in accordance with requirements of practical operation, so that, for example, the power of the gap may be varied in relatively large steps, or in small steps, or according to both methods.

With the foregoing general objects in view, as well as others which will be apparent to those skilled in the art from the following description, my invention consists in the novel construction and arrangement of parts, considered both broadly and specifically, hereinafter set forth and as pointed out in the appended claims.

For the sake of clearly illustrating and explaining the nature of the invention and its underlying principles so that the invention may be practised by those skilled in the art, I have shown in the accompanying drawings certain structural embodiments of the invention which at present I consider

the most advantageous. It is to be understood, however, that the invention is not confined to the detailed illustrative examples here given. On the contrary the invention 5 may be embodied in constructions differing widely therefrom in mechanical details and arrangement, while still embodying the broad principles of the invention and realizing its benefits to a greater or less extent.

10 In the accompanying drawings, illustrating certain especially desirable forms of apparatus within the invention,

15 Figure 1 is an end elevation of a spark gap apparatus, comprising a holder with spark gap units mounted thereon, the spark gap being here shown associated with other parts of a wireless transmitter;

20 Figs. 2 and 3 are a front elevation and a partial top plan, respectively, of said spark gap apparatus;

25 Figs. 4 and 5 are a longitudinal section and partial end view, respectively, of one form of spark gap unit or element employed;

30 Fig. 5^a is a fragmentary section on the line 5^a—5^a of Fig. 5;

35 Fig. 6 is a section of a slightly different gap unit construction;

40 Figs. 7 and 8 are a partial front elevation and a sectional end view, respectively, showing another type of holder for the gap units;

45 Figs. 9 and 10 are a top and side view, respectively, of a detail of the construction shown in Figs. 7 and 8;

50 Fig. 11 is a sectional view showing still another construction of spark gap unit;

55 Fig. 12 is an end view similar to Fig. 1, of another modified type of holder for the spark gap units, partly broken away for the sake of clearness; and

60 Fig. 13 is a front elevation partly in section, of the apparatus shown in Fig. 12, with the front part of the holder removed and some of the spark gap units omitted for the sake of clearness in illustration.

65 Referring first more particularly to the gap units themselves, a desirable form of unit is illustrated by way of example in Figs. 4 and 5, where 20 and 21 are circular spark gap plates or disks of brass or other suitable conducting material, having recesses adjacent faces to each of which is firmly secured, as by hard soldering, a sparking ring 22, which rings provide the actual 70 sparking surfaces and may therefore advantageously be of pure silver, which is especially suited to this purpose. The small distance between the two sparking rings, say one or two one-hundredths of an inch, for 75 instance, constitutes one elementary gap of the series comprised in the full gap distance. The two plates of the spark gap unit are secured firmly together by clamping means here shown as comprising a bolt 23, desirably 80 of bronze, whose head is arranged to exert

clamping pressure on plate 21, though insulated therefrom. To this end said bolt extends loosely through pressure washer 24, and through an ample clearance opening 25, in plate 21, and is threaded at 26 to engage the threaded bore 27, in plate 20. As here shown, the bore extends completely through the plate but is closed at its outer end by cover plate 28, soldered to plate 20. This is merely a manufacturing expedient, it being 90 simpler to do this than to bore a hole part way through the plate to an exact desired depth. An insulating washer 29 separates pressure washer 24 from plate 21; while insulating gasket 30 separates the relatively narrow coöperating bearing flanges or ribs provided on the adjacent faces of the spark gap plates near their peripheries. These bearing flanges or ribs are slightly rounded as indicated at 300 in order to insure efficient 95 and accurate seating of the coöperating disk members against the insulating gasket 30, the pressure on the gasket 30 being thus localized and the joint between the electrode members being thus tightly sealed. The coöperating pressure surfaces of the washer 24 and electrode 21 are similarly rounded as indicated at 240 for the same purpose. In order to secure effective seating of the head of bolt 23 against washer 24 in such manner 100 as to provide a sealed joint, it is desirable that the under surface 230 of said bolt head be beveled at a slightly greater angle than the coöperating bearing surface 241 of said washer. In practice, the angle of the surface 230 may be 45°, for example, while that of the surface 241 may be about 40°. This gives a linear bearing contact between the bolt and the washer so that when the bolt is turned down to seat against the washer it 105 grinds into the metal and gives a close sealed joint. As will appear hereinafter, it is not essential to employ the pressure or bearing washer 24; but it is very desirable to do so since in this way it is possible to avoid 110 abrading action of the bolt head on the insulating washer 29 incidental to direct contact of the bolt head therewith. It is evident that by means of the gap unit construction described, the two spark gap plates or 115 disks forming the elementary gap electrodes, are electrically insulated from each other, and the sparking surfaces are inclosed in an air-tight chamber. The described arrangement for clamping together the component 120 members of the gap unit while capable of wide variation in detail within the scope of the invention, insures accurate and uniform spacing apart of the sparking surfaces. When a number of gap units are assembled 125 in series, flange 210 of one unit coöperates with flange 200 of the next succeeding unit to space the head of bolt 23 away from plate 20 of such succeeding unit and thus to prevent short-circuiting an elementary gap. 130

- Provision is made for dissipating the heat generated by the spark gap units, and in the construction illustrated the gap is designed to be self-cooling, that is, to be operable 5 without a fan or other auxiliary cooling means. This construction departs radically from the prior practice in this art. Heretofore cooling fins or flanges have been cast on spark gap disks or plates, and have been of 10 the same material as the disk or plate, ordinarily brass. Furthermore such flanges have been of relatively very thick cross section. In such prior practice, the temperature gradient has been low, the difference in temperature 15 between the base of the fin or flange next to the electrode, and the outer extremity of such fin ordinarily not amounting to more than about 1° C. This former type of construction resulted in massive heavy spark 20 gap apparatus, as hereinbefore pointed out. In contrast to the prior practice, I have found that the use of thick heavy metal flanges or fins for the gap electrodes is entirely unnecessary, and that a very much 25 more efficient cooling effect is obtained by employing fins or flanges of relatively very thin cross section, most desirably of sheet metal, formed separately from the electrodes and attached thereto in heat conducting relation; and that by means of this improved 30 construction, the weight of spark gap apparatus can be reduced, for example, to one-third of the minimum weight at which it was possible to construct self cooled spark gaps 35 heretofore. In spark gaps constructed in accordance with this particular phase of the present invention, it has been found desirable in actual practice to have a relatively high temperature gradient such, for example as to give under usual operating 40 conditions a difference in temperature between the central and outer portions of the cooling flange or fin amounting to as much as 10° C.; and for the purposes of this invention, such 45 temperature gradient should ordinarily be high enough to give a temperature difference of not less than 3 or 4° C., that is to say, several times as great a temperature gradient as has been heretofore employed in this art. 50 In addition to the broad novelty involved in the use of relatively very thin heat dissipating flanges for the electrodes, and especially sheet metal fins, the present construction is further characterized, in the most desirable embodiment of the invention, by an 55 arrangement of said flanges or fins in such manner as to provide air circulation passages or channels in the nature of flues or chimneys, whereby systematic and efficient 60 circulation of cooling air over broad heat dissipating surfaces is accomplished. Evidently the broad principles involved in spark gap cooling means of the character described can be embodied in various forms 65 mechanically, but the construction here illustrated by way of example have given satisfaction in practice and is particularly desirable.
- Referring again to Fig. 4, the cooling means here shown comprises double rectangular flanges or fins 31, one or more such double flanges being provided for each gap plate. It is especially desirable to form each of these double flanges or fins of two sheets of highly conductive metal, such as 70 cold rolled copper, the sheets being centrally apertured and oppositely flanged as indicated at 32, where they fit snugly around and are soldered to the gap plate. The sheets are folded or lapped over each other and 75 most desirably soldered together at the corners or at points along one pair of opposite outer edges, as indicated at 33, the other pair of edges 34 being left substantially free. In use, the edges 33 are vertical, the 80 double fin arrangement thus acting like a chimney flue and favoring efficient air circulation upwardly over the heat dissipating surfaces provided by the copper sheets of the double flange. The rectangular box- 85 like construction of the double flanges, open at top and bottom and closed on the sides, acts like a flue or a chimney, the heat given off by the copper flanges when the gap is in use serving to establish a natural draft vertically over the flange surfaces, and thus 90 rendering unnecessary the employment of auxiliary cooling means. The same action occurs to a somewhat less extent in the spaces between the double flanges of each pair of 95 electrodes constituting a unit, and also between the flanges of successive units when 100 they are assembled in series.
- As a further aid in stiffening the double cooling flange construction, one or more 105 tongues 310 may be punched from one or both of the component metal sheets 31, as shown in Figs. 5 and 5^a, to form a brace between said sheets. For convenience in assembling the parts of a gap unit, three of 110 the four sheets comprised in the two double flanges are provided with three sets of alined holes 311, the radial distance of these holes from the axis of the gap unit being substantially equal to the outer radius of 115 the insulating gasket 30. With the aid of assembling rods extending through the several sets of alined holes, the insulating gasket can thus be accurately centered with 120 respect to the coöperating pressure flanges 300 of the gap electrodes. This is of considerable importance in order to avoid leakage of current between the electrodes. This provision for assembling the gap unit members is also a convenient means for properly 125 lining up the rectangular cooling flanges.
- The gap unit illustrated in Fig. 6 is very similar to that above described, the principal difference being in the form of the washer 24^a, the effective bearing diameter of 130

which is somewhat greater than in the unit of Fig. 4. This is rendered necessary by the fact that the plate 21^a of the gap unit is thinner than the corresponding plate 21⁵ shown in the corresponding gap unit of Fig. 4. Consequently it is desirable that the clamping pressure exerted by the bolt 23^a on the bearing washer 24^a be applied to the plate 21^a at points considerably nearer the

10 peripheral bearing flanges 300^a of the electrodes, in order to avoid affecting the elementary gap distance when the bolt is tightened up to clamp the electrodes together. Because of the greater diameter of the 15 washer 24^a, and the consequently smaller insulating air space between the edges of the washer, and the flange 210^a, the insulating washer 29^a is made cup shaped as shown to avoid any possibility of short circuiting the 20 elementary gap.

The type of spark gap unit illustrated in Fig. 11 involves the same general principles of construction as those hereinbefore described. The principal detailed differences 25 are the employment of triple cooling flanges 31^b in place of double flanges, and the employment of a clamping bolt 23^b whose head 23^c bears directly on insulating washer 29^b instead of through a protecting pressure 30 washer. As here shown the flanges 31^b engage shoulder 31^c formed on the peripheries of the electrode plates, this arrangement favoring stiffness and rigidity of the assembly. The bolt head may be slotted at 23^d 35 to receive a wrench, and the electrode 20^b may also be provided with wrench receiving recesses as indicated at 20^e, this arrangement being convenient in assembling the gap electrodes. The electrodes 20^b and 21^b may be 40 advantageously cutaway somewhat at the outer edges of the sparking rings as indicated at 201 to confine sparking strictly to the sparking rings.

The three typical constructions above 45 described for the spark gap units may be employed in spark gap apparatus of different operating powers, and may of course be varied in dimensions as required for service under different conditions. However, since 50 self cooled spark gap devices of the construction herein disclosed are broadly novel, and for the sake of affording concrete examples of self cooled spark gap units which will give satisfactory results in actual use, examples 55 of certain dimensions and proportions which have been demonstrated to be suitable will be given by way of explanation. Assume that fifteen gap units are to be employed in series for operation at full rated 60 power. On this assumption, spark gap units for two kilowatt operation, constructed in accordance with the showing of Figs. 4, 5 and 5^a may have the following principal dimensions: The silver spark rings 22 have 65 an inside diameter of .625 inch and an out-

side diameter of 1.25 inches; the brass electrode plates or disks are 2 inches in diameter and have a thickness of from .3 to .4 inch at the locality of the spark rings; the rectangular double cooling flanges are 6 inches 70 in vertical height and 5.25 inches in width; and the cold rolled copper of which the flanges are composed has a thickness of .022 inch.

Under the same assumptions, a spark 75 gap unit of the type illustrated in Fig. 6 and designed for operation at 1 kilowatt, may have approximately the same dimensions as specified above, but the electrode member 21^a may be thinner because less heat will 80 have to be dissipated, and for the same reason the cooling flanges may have a vertical height in this case of only 3.75 inches, and a width of 5.25 inches. The electrode member 20^a is of the same thickness as before in order 85 that it may not be sprung inwardly by the tension of the assembling bolt and the elementary gap distance thereby affected.

For 5 kilowatt operation, a unit of the construction shown in Fig. 11 may have 90 sparking rings whose outside diameter is 1.75 inches and inside diameter .625 inch; electrodes 2.50 inches in diameter and .4 to .5 inch thick at the region of the sparking rings; the outside dimensions of the triple 95 cooling flanges being 7 inches vertical height and 8 inches width. The same thickness of sheet copper may be employed as before, namely, .022 inch. This approximate thickness gives particularly good results. In general, it is not desirable to use metal thicker than about .05 inch for the cooling flanges of gap devices of the type herein disclosed.

The distance between adjacent cooling 100 surfaces in these multiple flange constructions is a point of considerable importance. I have found that, in general, with gap devices of the character herein described, best results are obtained when the spacing distance between adjacent fins is from .20 inch 105 to .40 inch. Above or below these approximate limits, the cooling effect decreases rapidly. A range of from .25 inch to .35 inch is especially desirable; and in the specific dimensioned examples above given, a spacing distance of .28 inch between the sheet copper fins of the double and triple cooling flanges was found most suitable under practical conditions. It is desirable also that the spacing between adjacent complete flanges 110 as well as between the component flange elements be within the limits just specified, uniformity of spacing favoring uniformity 115 in the gap performance.

It is to be understood that the foregoing 120 dimensions are in no sense limiting and are here given merely as illustrating typical practical constructions which have proved especially satisfactory in actual use, particularly with respect to self cooling capability. 125 130

The dimensions given may of course be varied considerably without departing from the invention and without sacrificing its substantial benefits.

- 5 It is also to be noted that while the gap units here illustrated each comprises a pair of electrodes coöperating to form a single elementary gap, the invention is not limited to such construction but contemplates broadly 70
- 10 the combination in a unitary structure of a plurality of electrodes coöperating to provide an elementary gap structure, several of such elementary gap structures or units being adapted for arrangement in series to 75
- 15 constitute a complete quenched gap, of which the several unitary parts are individually removable from the series without disturbing the other members thereof. 80
- 20 Spark gap units of the character hereinbefore described may be assembled in series in any suitable type of holder or support. 85
- Figs. 1, 2 and 3 illustrate a method of mounting and electrically connecting in series a plurality of spark gap units or 90
- 25 elements which I have found especially desirable in practice. As here shown, the gap units, which in this instance are of the type shown in Figs. 4 and 5, are supported on a substantial frame-work or holder of 95
- 30 insulating material, consisting of upright end members 35, and horizontal longitudinal bars 36, 36^a. In the present example, the spark gap holder is intended to be associated mechanically with other parts of a transmitter construction, and to this end the end members 35 are extended, as shown in Fig. 1, to support a condenser 37, and a panel 38 for certain of the transmitter helices (not shown). As the present invention is not 100
- 35 concerned with the details of these other parts, no further description of them is necessary. The spark gap units, of which there are fifteen in the present example, may be mounted between bars 36, 36^a, in any 105
- 40 suitable manner. In this specific embodiment of the invention, said bars are provided with a plurality of regularly spaced gap unit supporting devices which also serve to connect said units in series electrically. 110
- 45 Secured to the bar 36 in spaced arrangement are angular metal bracket plates 39, each having an inwardly extending contact piece 40, beveled on its upper edge to facilitate insertion of the gap units into the holder, 115
- 50 as will appear later. The distance between centers of adjacent contact pieces 40, is slightly greater than the over-all length of one of the spark gap units already described. Each contact piece is shouldered or reduced 120
- 55 in size at the point 41 to form a smooth joint with a pair of contact springs 42 secured to the opposite sides of the contact piece, said contact springs, in their most desirable form, extending downwardly and 125
- 60 inwardly at a slight angle, as shown. Each 130

of these contact springs has a double bend at its lower end as indicated at 43, constituting a supporting ledge or shoulder for a gap unit, and also constituting one member of an automatic circuit closer when such unit is removed. The springs secured to the adjacent faces of adjacent contact pieces 40 press against each other firmly in good metallic contact as shown at 44 (Fig. 3), when not supporting a gap unit, and thus co-operate to provide a separable stirrup or supporting device for the reception of such unit. These springs may be of any suitable form, but as here shown each consists of a narrow strip of conducting metal having a cut-out portion at 45 of such form that separating pressure on a pair of contacting springs results in a uniform bending of both springs back into substantially vertical position, instead of merely a bending of the lower portion of each spring. The advantage of this arrangement, which is very desirable though not indispensable, will appear hereinafter. At each end of the bar 36 are the half-plate 46, and the half-contact piece 47, corresponding to plate 39, and contact 40, respectively; and these end contacts 47, of which only one is shown in the drawing (Fig. 3), each carry only one contact spring 42. 95

The opposite bar 36^a, of the frame, also carries a series of plates and contact pieces 39^a and 40^a, corresponding generally to parts 39 and 40 before described, and arranged respectively opposite said parts in the same manner. The contact pieces 40^a are however provided with upwardly beveled extensions 48, which project forwardly over and beyond the bar 36^a at the front of the spark gap device. Half-plates 46^a and contact pieces 47^a at opposite ends of bar 36^a, correspond to parts 46 and 47 on bar 36. The contact pieces on bar 36^a are also provided with contact springs 42^a which are similar in all respects to contact springs 42 before described, and which also extend downwardly and a short distance inwardly toward the center line of the apparatus. 105

From the foregoing description, it will be seen that if one of the gap units shown in Figs. 4, 5 and 6 be inserted between two opposite pairs of adjacent contact members 40 and 40^a, with the overlapped edges 33 of the gap unit vertical, and then gently pushed downwardly, the corresponding pairs of adjacent contact springs 42 and 42^a will be sprung apart from the position shown at 44 in Fig. 3 and will be separated, each finally assuming a substantially vertical position and holding between them the double flanges or fins of the spark gap unit, the outer lower edge of each double fin resting on the stirrup or supporting portion of a contact spring, while the vertical portion of the spring is pressed firmly and lies flat against 130

the opposite outer surfaces of the gap unit flanges, making good electrical contact therewith. Rapid insertion of the gap units is much facilitated by the upward double bevel 5 on contact pieces 40 and 40^a, which serves to guide the gap unit flanges into proper position. When all of the fifteen gap units are thus inserted in the spaces provided for them in the spark gap holder, it is apparent 10 that said spark gaps are electrically connected in series. That is to say, starting with binding post 49, which is electrically connected to contact piece 47, current may pass through the first contact spring 42 to the 15 copper flange 31 of the gap unit shown at the extreme left in Figs. 2 and 3. The current then passes through disks 20, sparking ring 22, jumps the minute gap to the coöperating spark ring 22, passes thence 20 through disk 21 and its attached flange 31 to the second contact spring 42 of the series, and from there goes to the first complete contact piece 40. The passage of the current through the succeeding gap units of the 25 series is the same as already described for the first unit, it being remembered that the contact pieces 40^a and spring clips 42^a on the bar 36^a act similarly to 40 and 42 in conducting current through the series. Inci- 30 dentally current passes to some extent directly from one unit to the next through flanges 200, 210, where these happen to abut, as they may in some cases. Binding post 50 (Fig. 2) at the opposite end of the series 35 of gap elements is electrically connected to the half contact piece 47 at that end of the apparatus, so that if the apparatus is connected in the primary oscillating circuit by means of binding posts 49 and 50, which are 40 arranged at opposite ends of the holder and are electrically connected respectively to the half-contacts 47, and if none of the gap elements is cut out of the circuit or short-circuited, the spark gap apparatus will func- 45 tion in the system in the manner characterizing a quenched spark gap comprising fifteen elementary gaps.

It is especially important to notice that if for any reason it is desirable to remove 50 any one of the gap units, or several units, for repair or for any other purpose, it is only necessary to lift out the unit or units in question, whereupon the spring contact and supporting clips 42 and 42^a holding the 55 removed unit or units spring together as indicated at 44 in Fig. 3 thus automatically closing the break in the circuit at that point.

Another desirable and very important feature of the apparatus is the provision where- 60 by the number of gaps in circuit may be readily changed so as to enable employment of the gap in connection with transmitting systems of different power. Thus, a two kilowatt spark gap device, constructed in 65 accordance with my invention, may have its

connections so varied as to adapt it instantly for use in a one kilowatt or one-half kilowatt transmitter for example. Furthermore, in conjunction with or independently of the provision for rapidly changing the 70 power of the gap, it is very desirable to provide means for varying the number of gaps in circuit not only by comparatively large jumps or groups, but also in small steps whereby fine adjustment may be had 75 at whatever power the gap is set to operate. Means adapted to accomplish both these objects will now be described.

As has been stated above, in the absence of any short-circuiting of one or more gap units, current will pass through the entire series between the binding posts 49 and 50. In order, however, to provide for rapidly changing the number of gaps effectively in circuit, so that the apparatus can be operated 80 at two or more predetermined different powers, I provide a short-circuiting switch device comprising in this instance three conductive radial switch arms 51, 52 and 53, which are mounted at different angles on 85 a metal switch rod or shaft 54 which extends parallel to the bars 36 and 36^a and is journaled at the front of the apparatus in for- 90 wardly projecting extensions of the end members 35 of the apparatus frame, as 95 shown. The switch arms are mounted to turn with the switch rod, and to this end the rod may conveniently be square in cross section; but the switch arms are adjustable therealong into different positions opposite 100 any one of the projecting contacts 48, suitable detent means (not shown) being em- 105 ployed to releasably hold each switch arm in any adjusted position lengthwise of the switch rod. Each switch arm terminates in 110 a double spring brush as shown, adapted to engage the forward projections or blades 48 of contact pieces 40^a. By rotation of the switch rod, any one of the switch brushes can be made to engage the contact 48 oppo- 115 site which it has been set. The switch rod 54 is electrically connected to binding post 50 in any convenient manner, as for ex- 120 ample, by way of conductor 55, which leads to half-contact 47^a at the right, thence through the cooling flange of the end gap unit to the half-contact (not shown) to which binding post 50 is connected, and if the switch rod be turned by means of its operating handle 56 to bring any one of the 125 switch brushes thereon into engagement with the contact 48 opposite which that partic- 130 ular switch arm has been set, all the gap units to the right of that switch arm will be short circuited, and the number of gaps actually in service in the system will thereby be reduced. It frequently happens, how- ever, that in operating at any given power, finer adjustment is required to obtain a note of the proper clearness than would be ob-

tainable by means of the power changing device with its several switch arms set a considerable distance apart. Accordingly I provide an auxiliary short-circuiting device 5 which may be termed a note clearer, this device being of such character as to enable an increase or reduction of the number of gap elements in series by one gap element at a time, without regard to the particular setting 10 of the power changer switch. In the form of apparatus shown in Figs. 1, 2 and 3, this auxiliary device or note clearer consists of four switch arms 57, 58, 59 and 60 fixed at different angles on a conducting switch rod 61, which extends lengthwise of the apparatus parallel to switch rod 54, and is similarly journaled in end members 35 of the apparatus frame. That part of switch rod 61 not occupied by the switch 15 arms may be incased in an insulating sleeve 61^a. The said switch arms are positioned respectively opposite the four spark gap units at the left end of the apparatus as shown in Figs. 2 and 3, so that by turning switch rod 61 with the aid of operating handle 62, the terminal brushes on four switch arms of the note clearer may be made to engage successively contact pieces 57^a, 58^a, 20 59^a and 60^a, which are mounted on the front vertical face of bar 36^a, and each of which is 25 electrically connected to one of the contact pieces 48. The switch rod of the note clearer is electrically connected as by conductor 62, and screws 63 and 64, to contact piece 47^a on bar 36^a. This contact piece is in turn electrically connected by way of the flange of the last gap unit in series to binding post 49. Consequently, with switch arm 57 of the note clearer in engagement with 30 contact 57^a, the first gap unit at the left will be short circuited; and assuming that switch arm 51 of the power changer is in the position shown in Fig. 3, there will evidently be only five gaps actually in use. If switch arm 58 be now brought into engagement with contact 58^a, another gap is short circuited. Similarly, three and four gaps can be short circuited by means of switch arms 35 59 and 60, respectively. Lugs 56^a adjacent handle 56, cooperating with a stationary stop pin 56^b, limit the turning movement of the power changer switch rod, and similar means (not shown) may be provided for the note clearer. It will be noted that the 40 double spring contact brushes in which the note clearer switch arms terminate are considerably elongated in the direction of swing. This is a desirable feature because, in operating the note clearer, no brush leaves 45 its coöoperating contact until the next succeeding brush has engaged its contact. This practically eliminates sparking.

It is desirable to employ both the power changer switch device and the note clearer 50 in the apparatus, not only because the note

clearer is useful in adjusting to exactly the proper note desired, but also for another reason. Assuming the gap to be in operation with a certain number of gap units in series, if one of the units should give 55 trouble, it can be immediately removed by the operator in the manner hereinbefore described, and the note clearer can then be shifted to add one more unit to the series. The circuit having been automatically 60 closed when the defective unit was removed, in the manner already pointed out, the apparatus is thus restored to its original condition, the necessary operations to effect this having required but a moment. It is evident therefore that the apparatus described 65 possesses flexibility of operation to a maximum degree and can be operated in practice with the minimum amount of delay and trouble. Such considerations are of the utmost importance in practical radio work. It is obvious that many changes can be made in the mechanical details of the holder apparatus above described while realizing the benefits of the invention wholly or in 70 part. For example, the spark gap units can be mounted on a holder of the type shown in Figs. 7 and 8, and under certain conditions this type of holder has distinct advantages on account of certain simplified features of construction and additional desirable characteristics. This modified type of mounting has at least one feature in common 75 with that previously described, that is, an arrangement whereby removal of any one 80 of the spark gap elements is necessarily accompanied by the closing of the circuit at the point where the spark gap element was removed, the operation of removing the gap element in this instance requiring movement 85 of a retaining device into such position as to establish the circuit. In the construction shown in Figs. 7 and 8, the spark gap units are supported between the upper and lower 90 insulating bars 65 and 66, between which 95 the gap units are inserted and removed laterally, as compared to the vertical insertion and removal characterizing the form of mounting first described. Mounted on the 100 side of the upper bar are metal plates 67, 105 with downwardly depending lugs 68, to each of which lugs is pivoted at 69 a combined latch and switch device 70, consisting of two 110 resilient strips or blades 71 and 72 of metal secured together and electrically connected 115 as at 73 by any suitable means. At the rear, member 71 is bent to provide a keeper 74, this keeper also sloping rearwardly from the upper edge of member 71 as clearly 120 shown in Figs. 8 and 10, for a purpose which 125 will presently appear. At the front, member 71 is provided with a bent portion affording a lifting lug 75 and a retaining lug or keeper 76. The member 72 normally presses at 77 against member 71, but when the for- 130

ward end of the combined retaining and switch member is lifted by means of lug 75 into the dotted line position shown in Fig. 8, the forward portion of the combined device 5 operates as a knife switch to engage contact 78 which is supported by means of bent brackets 79 to the plate 67 before mentioned. On the lower supporting bar 66 are mounted metal supporting shoes or members 80, each 10 said member being directly below the corresponding latch and switch device 70. These supporting members 80 are beveled forwardly as indicated at 81, so that a gap unit may be readily thrust between a pair of 15 said members, the arrangement being such that both double flanges of the gap unit are supported by the broadened bases of two adjacent members. The method of inserting and removing gap units from the complete 20 series in this type of mounting is obvious. The latch and switch device 70 being in the position indicated in dotted lines in Fig. 8, the unit may be readily inserted horizontally from the front, after which the device 70 is 25 turned down into the position shown in full lines, with blades 71 and 72 pressing against the upper edges of flanges 31 of an adjacent pair of gap units, while keepers 74 and 76 substantially engage the rear and front 30 edges, respectively, of the flange of one of the units and prevent displacement thereof. Any desired number of gap units can thus be supported by the holder and electrically connected in series. If now it be desired to 35 remove a gap unit, the member 70 is lifted into dotted line position by means of lug 75, whereupon the rearwardly sloping keeper 74 swings down to positively engage the rear edge of the aforesaid flange, slightly tipping 40 the unit forward just after the retaining portion 76 at the front has been swung out of the way. The unit can then be withdrawn readily. It will be seen also that since the member 70 is in electrical contact 45 with the plate 67 to which it is pivoted, and since when said member is swung upwardly it makes electrical contact through 78 and 79 to the next succeeding plate 67 in series, the circuit which would otherwise be entirely 50 open by the removal of one gap unit is necessarily closed by the act of removing such unit. The two plates 67 at the opposite ends of the series are of course electrically connected in circuit with the other parts of 55 the transmitter system by suitable means. Power changer and note clearer devices of the character before described may be applied to spark gap apparatus employing this modified type of mounting, a power changer 60 switch rod being indicated at 82 and one of its switch arms at 83, the construction in this respect being similar to that already set forth.

So far as concerns fundamental principles 65 of construction and operation, the spark gap

apparatus illustrated in Figs. 12 and 13 is practically the same as that illustrated in Figs. 1, 2 and 3. It embodies certain differences in structural detail, however, which afford some practical advantages. It will 70 be noted in particular that in the apparatus of Figs. 12 and 13, the power changer and note clearer devices are arranged at the rear of the series of spark gap units instead of being placed at the front as in the apparatus 75 of Figs. 1, 2 and 3. This makes it possible to materially shorten the leads connecting the spark gap in circuit with the other parts of the transmitter, that is, the connections to the condenser on the one hand and to 80 the primary of the oscillation transformer on the other. This reduces the self inductance of the primary oscillation circuit and permits operation at lower wave lengths than would otherwise be possible. As shown, 85 the conducting power changer shaft 100 is rotatably mounted at its ends in the holder frame at a point between the panel 38 and the spark gap, and carries switch devices 101 arranged at different angles on the shaft 90 which is conveniently squared as before, the switch arms being adjustable longitudinally of the shaft in the manner already described. The switch rod may be turned by means of 95 operating handles 102, of which one may be provided at each end. At a convenient locality, practically at the middle in this instance, the shaft 100 is round in cross section and at this locality an adjustable double spring brush 103 embraces the shaft, bearing 100 upon it with sufficient pressure to insure good electrical contact while permitting relative rotation of the shaft with respect to the brush. To the other extremity of brush 103 is secured another brush or spring clip 104, 105 the brush being manually operable to move the clip 104 into or out of engagement with the blade contact 105 which is electrically connected to primary switch arm 106 of the transmitter wave changer. This switch arm 110 can be swung by means of operating shaft 107 and hand wheel 108, over a series of 110 studs 109 which are respectively connected to points on the primary helix of the oscillation transformer. 115

The note clearer device comprises in this embodiment of the invention a rod 110 of insulating material rotatably journaled at its ends in the holder frame and carrying a metal sleeve 111, to which are secured the 120 note clearer switch devices 112, five in number in this instance. These are arranged at different angles in the same manner as the corresponding switch devices of the note clearer shown in Figs. 1 to 3, and their function and mode of operation are essentially similar in all respects. The note clearer switch rod can be turned by means of operating knob 110^a. An adjustable double 125 spring contact brush 113 bears upon the 130

sleeve 111 and is electrically connected at 114 to condenser 37.

The path of the current between the condenser and the primary helix P of the transmitter can, therefore, be traced as follows: Starting with the condenser, current flows through brush 113 to sleeve 111, thence through one of the note clearer switch devices 112 to the contact 57^a with which said switch device is engaged, thence through the series of gap units being used to whichever one of the contacts 48 is engaged by one of the switch devices 101; and from there through shaft 100 and brushes 103 and 104, blade 105 and switch arm 106 to a point on the transformer primary represented by one of the studs 109.

This arrangement not only permits the use of shorter wave lengths and thereby increases the effective range of operation, but it also has the further advantage that such spark gap units as are not actually being used are entirely cut out of circuit; whereas in the apparatus shown in Figs. 1, 2 and 3, the spark gap units not in service are in a sense simply shunted by the short circuiting action of the power changer and note clearer. It is found that the arrangement of Figs. 12 and 13 results in somewhat more perfect performance of the spark gap, although the arrangement first described is entirely satisfactory for all practical purposes.

As a matter of convenience it is desirable that in operating the power changer switch and the note clearer switch, the operator may be able to tell by the sense of touch the points at which the several switch devices 101 and 112 are in operative position. To this end, the particular apparatus shown in Figs. 12 and 13 is provided with detent means comprising, in the case of the power changer switch, a leaf spring 113^a having a forked upper end provided with sharp angular bends 114^a which are adapted to enter coöperating notches formed on the face of a collar 115^a, secured to the shaft 100. The turning movement of shaft 100 may be limited by means of a stop 56^a formed on the leaf spring 113^a, said stop lying in the path of lugs 56^c formed on the collar 115^a. Releasable detent mechanism similar to that described for the power changer switch may also be provided for the note clearer, as indicated at 113^b, 114^b and 115^b. A limiting stop device (not shown) may also be employed with the note clearer switch.

The apparatus illustrated in Figs. 12 and 13 while suitable for spark gap apparatus of any desired power is typical of a 1 kilowatt spark gap which has given satisfaction in actual use. As here shown, the spark gap units 116 may be of the type illustrated in Fig. 6, with the vertical dimension of the rectangular cooling flanges less than the horizontal dimension. The arrangement for

supporting the gap units and electrically connecting them in series is substantially as hereinbefore described in connection with Figs. 1, 2 and 3.

As before stated, the present invention 70 enables the construction of self cooled quenched gaps which are much lighter and less bulky than gaps of the same operating power heretofore constructed. In a specific instance, a 2 kilowatt spark gap constructed 75 in accordance with the present disclosure weighed about 50 pounds, whereas heretofore the minimum weight for a 2 kilowatt self cooled quenched gap was 150 pounds. Moreover the gap constructed in accordance 80 with my invention, occupied very much less space and heated up to only about 65 degrees C., whereas the old type of gap operating under exactly parallel conditions heated up to about 120 degrees C. It will be evident 85 also, in addition to the other advantages of the invention hereinbefore pointed out, that by providing separate self-contained gap units, whose component electrode members are assembled and secured together in accurate spaced relation by individual clamping means the elementary gap distances are not disturbed in any way when the gap units are assembled in series as herein set forth; whereas in the former practice, all the electrode plates or disks of the complete gap were clamped together by pressure means acting on the series as a whole, an arrangement which invariably operated to disturb the elementary gap distances. 90

Although certain specific embodiments of the broad invention are illustrated in the drawings and have been set forth in detail in the foregoing description for purposes of explanation, it is to be understood that 105 the invention contemplates a wide range of variations in mechanical details of construction and arrangement, and comprises all such variations as fairly come within the scope 110 of the appended claims.

What I claim is:

1. A spark gap device comprising a pair of electrode members insulated from one another and having coöperating annular sparking surfaces disposed in parallel closely 115 spaced relation, in combination with means extending between said members centrally of said sparking surfaces and serving to hold said members firmly together in operative relation, said device constituting a removable gap unit adapted for use in series 120 with similar gap units in a complete spark gap.

2. A spark gap device comprising a plurality of electrode members insulated from 125 one another and having coöperating annular sparking surfaces disposed in substantially parallel closely spaced relation, in combination with transversely disposed fastening means extending within the inner peripheries 130

- of said sparking surfaces and serving to clamp said members together in operative relation, said device constituting a removable gap unit adapted for use in series with 5 similar gap units in a complete spark gap.
3. A spark gap device comprising a pair of electrode members insulated from one another and having coöperating circular annular sparking surfaces disposed in parallel 10 closely spaced relation, in combination with a bolt extending within the inner peripheries of said sparking surfaces, said bolt threading into one of said members and extending through the other said member, said bolt 15 being insulated from such other member but arranged to clamp the same in operative relation to the first member.
4. A spark gap device comprising a pair of electrode members insulated from each 20 other, a clamping bolt threading into one of said members and extending through an opening in the other member but out of contact therewith and having a suitable head, and a bearing washer insulated from such 25 other member, but arranged to transmit clamping pressure thereto from the bolt head.
5. A spark gap device comprising electrode members insulated from each other, said members having coöperating sparking 30 surfaces on their adjacent faces, and having their opposite non-adjacent faces recessed, in combination with means holding said members together and disposed wholly between the outer planes of said non-adjacent 35 faces.
6. A spark gap device comprising a pair of plate electrodes having coöperating sparking surfaces, a headed bolt extending through one electrode but insulated therefrom and anchored to the other electrode, 40 and a washer disposed between the bolt head and the first electrode but insulated from the latter, the coöperating surfaces of said washer and bolt head being formed to localize the pressure between them.
7. A spark gap device comprising a pair of plate electrodes suitably secured together in operative relation as a unit, and a double cooling flange of sheet metal on each member, 45 each double flange having its edges connected at two opposite localities and free at two other opposite localities.
8. A spark gap device comprising a pair of plate electrodes suitably secured together 50 in operative relation as a unit, and a double rectangular cooling flange on each member, said flange having one pair of opposite edges substantially continuously connected, and the other pair of opposite edges substantially 55 free.
9. A spark gap device comprising coöperating sparking electrodes, in combination with cooling means in heat conducting relation to said electrodes and consisting of con- 60 ducting material formed to provide a flue 65 for circulation of cooling air.
10. A gap device comprising coöperating spark gap electrodes, in combination with metal cooling fins or flanges of such thinness that the temperature gradient in said fins is 70 relatively high, said fins being formed to provide flues for passage of cooling air upwardly.
11. A spark gap device comprising plate electrodes having coöperating sparking surfaces on their adjacent faces, said adjacent faces being also provided with coöperating bearing flanges or ribs surrounding said 75 sparking surfaces and having narrow rounded bearing surfaces, an insulating gasket interposed between said coöperating bearing flanges or ribs, and means clamping said members together.
12. Quenched spark gap apparatus comprising a plurality of spark electrodes co-operating to provide serially related elementary gaps in combination with switch means operable to vary, by relatively large steps, the number of such gaps effectively in circuit, and additional switch means operable 80 to vary, by relatively small steps, the number of such gaps effectively in circuit.
13. Quenched spark gap apparatus comprising a holder, a plurality of spark electrodes arranged in a plurality of structurally 85 separate groups individually removable from said holder, said electrodes coöperating to provide serially related gaps, in combination with switch devices operable to vary the number of such gaps effectively in circuit by 90 relatively large steps and by relatively small steps, respectively.
14. Quenched spark gap apparatus comprising a plurality of spark gap units electrically connected in series, in combination with switch means adapted for connection in an oscillation circuit and operable to make connection with different gap units near one end of the series, and additional switch means also adapted for connection in an oscillation 95 circuit and operable to make connection with different gap units in the remainder of the series.
15. Quenched spark gap apparatus comprising a plurality of spark gap units electrically connected in series, in combination with switch means adapted for connection in an oscillation circuit and operable to make connection consecutively with a certain number of gap units beginning at one end of the 100 series, and additional switch means also adapted for connection in an oscillation circuit and operable to make connection in regular sequence with different gap units in the remainder of the series.
16. Quenched spark gap apparatus comprising a plurality of spark electrodes co-operating to provide serially related ele- 105 110 115 120 125

mentary gaps, in combination with switch means operable to vary the number of such gaps effectively in circuit by definite steps, said switch means being adjustable to alter

5 the extent of said steps.

17. Quenched spark gap apparatus comprising a plurality of spark electrodes co-operating to provide serially related elementary gaps, in combination with switch

10 means adapted for connection in an oscillation circuit and having a plurality of switch arms movable to make electrical connection selectively with different spark electrodes and thereby to vary the number of gaps ef-

15 fectively in circuit.

18. Quenched spark gap apparatus comprising a holder, a plurality of spark gap units of the plate type mounted on said holder and electrically connected in series,

20 contact devices each electrically connected to a point in the gap series, and switch means adapted for connection in an oscillation circuit and movable to engage said contact devices selectively in predetermined

25 sequence and thereby to vary the effective number of gap units in circuit.

19. Quenched spark gap apparatus comprising a holder, a plurality of spark gap units mounted thereon and electrically connected in series, a plurality of contact devices electrically connected to different points in the series of gap units, an elongated switch member having a plurality of switch arms spaced apart along said member and extending radially therefrom at different angles, said switch member being rotatable to bring said switch arms successively into engagement with certain of said contact devices.

40 20. Quenched spark gap apparatus comprising a holder, a plurality of spark gap units mounted thereon and electrically connected in series, a plurality of contact devices electrically connected to different

45 points in the series of gap units, an elongated switch member having a plurality of switch arms spaced apart along said member and extending radially therefrom at different angles, said switch member being ro-

50 tatable to bring said switch arms successively into engagement with certain of said contact devices, said switch arms having contact portions so arranged that none of the switch arms breaks contact with its corre-

55 sponding contact device until another switch arm has begun to engage its corresponding contact device.

21. Quenched spark gap apparatus comprising a plurality of co-operating gap units, in combination with switch means operable to make electrical connection in sequence with different gap units of said plurality for the purpose of including different numbers of said units in an oscillation circuit,

the arrangement being such that connection to one unit is not broken until connection to another has been made.

22. Quenched spark gap apparatus comprising the combination, with a holder, of a plurality of individually removable spark gap units electrically connected in circuit, the arrangement including means operable by removal of a gap unit to prevent a break in the circuit by such removal.

23. Quenched spark gap apparatus comprising the combination, with a holder provided with conductive supporting devices, of a plurality of spark gap units supported and connected in circuit by said devices, the arrangement being such that removal of a gap unit closes the circuit at that point.

24. Quenched spark gap apparatus comprising the combination, with a holder having supporting devices co-operating in pairs to support individually removable spark gap units and to connect said units in circuit, said devices being also operable to prevent a break in the circuit when a unit is removed.

25. Quenched spark gap apparatus comprising, in combination, parallel supporting members, spark gap units individually insertible between said supporting members, and means arranged to receive and hold said gap units in position between said supporting members, said means also serving to electrically connect said gap units in series while permitting them to be individually withdrawn from the series.

26. Quenched spark gap apparatus comprising, in combination, substantially horizontal parallel bars provided with a plurality of opposed pairs of depending supporting devices, and co-operating spark gap units having cooling flanges arranged to engage said supporting devices.

27. Quenched spark gap apparatus comprising holder means provided with a plurality of insulated conductive supporting devices, and co-operating spark gap units having cooling flanges arranged to engage said supporting devices.

28. Quenched spark gap apparatus comprising, in combination, substantially horizontal parallel bars provided with a plurality of opposed pairs of depending conductive supporting devices, and spark gap units having cooling flanges arranged to engage said supporting devices, said devices being arranged to connect the gap units in series.

29. Quenched spark gap apparatus comprising, in combination, substantially horizontal parallel bars provided with a plurality of opposed pairs of depending contact springs, and spark gap units arranged to engage said contact springs and to be connected thereby in series, said contact

springs being arranged to automatically close a break in the circuit occasioned by removal of a gap unit.

30. Quenched spark gap apparatus comprising, in combination, substantially horizontal parallel bars provided with a plurality of opposed pairs of depending flat contact springs formed to offer substantially uniform resistance at all points to an applied bending force, and spark gap units having flat cooling flanges engaging said contact springs under pressure, and the units being thereby connected in series.

31. A spark gap holder comprising parallel supporting bars of insulating material, and a plurality of electrically connected supporting devices mounted on each bar, each such device comprising a pair of resilient contact members which tend to remain in contact but which are separable by insertion of a spark gap unit therebetween, each such device on one bar being adapted and arranged to coöperate with another of said devices on the other bar to support a spark gap unit and to electrically connect it with adjacent units.

32. A spark gap holder comprising a pair of insulating bars spaced apart and substantially parallel, a plurality of gap unit holding members carried by said bars and adapted to engage and connect in series spark gap units, contact devices electrically connected, respectively, to certain of said holding members, and a rotatable switch device coöperating with said contact devices and adapted for connection in an oscillation circuit.

33. A spark gap holder comprising, in combination, an insulating mounting frame or base including substantially parallel spaced insulating bars, a plurality of gap unit holding members carried by said bars and adapted to engage and connect in series spark gap units, a series of contact devices connected to certain of said holding members and arranged adjacent one of said bars and substantially parallel thereto, a switch device including a conductive switch rod rotatably mounted on said frame substantially parallel to said bars and adjacent said contact devices and having radial contact arms mounted at different angles on said switch rod and arranged to engage certain of said contact devices in regular sequence when the switch rod is rotated.

34. A spark gap holder comprising, in combination, an insulating mounting frame or base including substantially parallel spaced insulating bars, a plurality of gap unit holding members carried by said bars and adapted to engage and connect in series spark gap units, a series of contact devices connected to certain of said holding members and arranged adjacent one of said bars and substantially parallel thereto, a switch

device including a conductive switch rod rotatably mounted on said frame substantially parallel to said bars and adjacent said contact devices and having radial contact arms mounted at different angles on said switch rod and arranged to engage certain of said contact devices in regular sequence when the switch rod is rotated, a second switch device operable to engage certain others of said contact devices, and means adapting both switch devices for connection in an oscillation circuit.

35. A spark gap holder comprising an insulating supporting structure, means on said supporting structure for mounting thereon a plurality of spark electrodes electrically connected in series, in combination with two separate switch devices mounted on said structure and operable to include in circuit between them a variable number of such electrodes, and means for directly connecting both switch devices in an oscillation circuit.

36. Quenched spark gap apparatus comprising, in combination, a plurality of structurally separate spark gap units each comprising coöperating electrodes provided with multiple cooling flanges consisting of spaced component flange elements suitably connected together, and means maintaining said gap units in operative assembly, the arrangement being such that the adjacent multiple flanges are spaced apart a distance substantially equal to the spacing of the component flange elements.

37. Quenched spark apparatus comprising a plurality of coöperating spark gap units, in combination with means for adjusting the circuit relation of said units for operation at different selected powers, and means for adjusting the character of the note produced at each operating power.

38. Quenched spark gap apparatus comprising the combination, with a holder, of a plurality of coöperating electrode plates or disks supported thereby, said electrode plates or disks being arranged in electrically connected units, each unit having its component plates or disks secured together in operative relation independently of the other units, and each unit being insertible into and removable from the apparatus without disturbing the other units.

39. A spark gap device comprising coöperating spark electrodes, in combination with relatively thin coöperating cooling fins spaced apart a distance of between .2 inch and .4 inch as approximate limits, said cooling fins being constructed of highly conductive sheet metal and being arranged to provide upright flue means.

40. In radio transmitter apparatus, the combination with oscillation circuit connecting terminals, of a quenched spark gap, two switch devices mounted closely adjacent

said terminals and operable to include a variable proportion of said spark gap in circuit, and means for connecting said switch devices to said terminals.

- 5 41. In radio transmitter apparatus, the combination, in an oscillation circuit, of a quenched spark gap, two switch devices operable to include between the main circuit a variable proportion of said gap, and leads 10 connecting said switch devices respectively in said oscillation circuit, the spark gap being otherwise unconnected in the circuit.

- 15 42. In radio transmitter apparatus, the combination, with a wave change switch, and a condenser, of a quenched spark gap, two switch devices adjustable to include between them in circuit a variable proportion of said spark gap, and means for electrically connecting one of said switch devices to 20 said wave change switch and the other switch device to said condenser.

- 25 43. In radio transmitter apparatus, the combination, with a suitably mounted wave change switch, and a condenser and a quenched spark gap mounted substantially therebelow, of two switch devices located substantially between said spark gap and said condenser and respectively connected to 30 said wave change switch and to said condenser, said switch devices being adjustable to include between them a variable proportion of said spark gap.

- 35 44. Spark gap apparatus, comprising a plurality of independently removable spark gap units connected in series, and means for automatically closing the circuit between adjacent gap units when a gap unit is removed.

45. A unit spark gap, comprising a plurality of electrode plates assembled together

flatwise and provided with annular sparking plates the sparking faces of which are spaced apart to provide a spark gap space between them, the electrode plates having bearing faces extending about the sparking plates and spaced therefrom and being secured together with an insulating and air-excluding packing between their bearing faces by a single central screw bolt extending through an opening in one of the plates and through the openings in the sparking plates and into a blind tapped hole in the other electrode plate, insulating and air-excluding packing being provided between the head of the screw bolt and the walls of the opening in the electrode plate through 55 which the bolt extends.

46. Spark gap apparatus, comprising a plurality of gap unit holders each formed of a pair of spring conducting arms to bear against and support a gap unit and through 60 which electrical connection is made to the opposite sides of the gap unit, a terminal connected to the outer arm of each end holder and other terminals connected each to the adjacent arms of two adjoining holders, two contact members for making contact with said terminals to connect the holders in the circuit, and means for causing a relative movement between said contact members for varying the number of holders 65 connected in the circuit and for moving said contact members together for connecting any desired series of the holders in the circuit.

In testimony whereof I hereunto affix my 75 signature.

FRITZ LOWENSTEIN.
